(57) **CLAIM**

The ornamental design for a combined container and nozzle, as shown and described.

DESCRIPTION

FIG. 1 is a perspective view of a combined container and nozzle showing my new design wherein the nozzle is removed;

FIG. 2 is a front elevational view thereof;

FIG. 3 is a rear elevational view thereof;

FIG. 4 is a left side elevational view thereof;

FIG. 5 is a right side elevational view thereof; and

FIG. 6 is a top plan view thereof.

FIG. 7 is a bottom plan view of the nozzle portion shown in FIG. 1. Portions in broken lines are for illustrative purpose only and form no part of the claimed design.

FIG. 8 is an enlarged front elevational view of the nozzle portion of FIG. 1 along the line 8—8 of FIG. 2;

FIG. 9 is an enlarged rear elevational view thereof along the line 9—9 of FIG. 3;

FIG. 10 is an enlarged left side elevational view thereof along the line 10—10 of FIG. 4;

FIG. 11 is an enlarged right side elevational view thereof along the line 11—11 of FIG. 5;

FIG. 12 is a top plan view thereof; and,

FIG. 13 is a bottom plan view thereof.
